(57) **CLAIM**

The ornamental design for a miter block, as shown and described.

DESCRIPTION

FIG. 1 is a perspective view of a miter block, as taken from above;

FIG. 2 is a top view thereof;

FIG. 3 is a bottom view thereof;

FIG. 4 is a perspective view thereof, as seen from below; FIG. 5 is a side view thereof, as taken from the right side of FIG. 2;

FIG. 6 is a side view thereof, as taken from the left side of FIG. 2;

FIG. 7 is a side view thereof, as taken from the upper side of FIG. 2;

FIG. 8 is a side view thereof, as taken from the lower side of FIG. 2;

FIG. 9 is a perspective view of a second embodiment of a miter block, as taken from above;

FIG. 10 is a top view thereof;

FIG. 11 is a bottom view thereof;

FIG. 12 is a perspective view thereof, as seen from below; FIG. 13 is a side view thereof, as taken from the right side of FIG. 10;

FIG. 14 is a side view thereof, as taken from the left side of FIG. 10;

FIG. 15 is a side view thereof, as taken from the upper side of FIG. 10;

FIG. 16 is a side view thereof, as taken from the lower side of FIG. 10;

FIG. 17 is a perspective view of a third embodiment of a miter block, as taken from above;

FIG. 18 is a top view thereof;

FIG. 19 is a bottom view thereof;

FIG. 20 is a perspective view thereof, as seen from below; FIG. 21 is a side view thereof, as taken from the right side of FIG. 18;

FIG. 22 is a side view thereof, as taken from the left side of FIG. 18;

(Continued)

FIG. 23 is a side view thereof, as taken from the upper side of FIG. 18; and,
 FIG. 24 is a side view thereof, as taken from the lower side of FIG. 18.
 The broken lines show portions of the article that form no part of the claimed design.
